UNITED STATES PATENT OFFICE.

ALCORN RECTOR, OF NEW YORK, N. Y.

DESIGN FOR A GAS-LAMP.

No. 38,646.

Specification for Design.

Patented July 2, 1907.

Application filed April 11, 1907. Serial No. 367,712. Term of patent 14 years.

To all whom it may concern:

Be it known that I, ALCORN RECTOR, a citizen of the United States, residing in the city, county, and State of New York, have invented a new, original, and ornamental Design for Gas-Lamps, of which the following is a specification, reference being had to the accompanying drawing, forming part thereof.

The figure is a side elevation of a gas lamp showing my new design.

I claim:

The original design for a gas lamp, as shown.

ALCORN RECTOR.

Witnesses:

WARREN B. HUTCHINSON,
WILLIAM S. DENISON.
